UNITED STATES PATENT OFFICE.

SEBASTIAN G. BRINKMAN, OF NEW YORK, N. Y., ASSIGNOR TO THE NEW YORK ELECTRIC MOTOR AND VENTILATOR COMPANY, OF SAME PLACE.

ELECTRIC MOTOR.

SPECIFICATION forming part of Letters Patent No. 570,424, dated October 27, 1896.

Application filed June 27, 1895. Serial No. 554,176. (No model.)

To all whom it may concern:

Be it known that I, SEBASTIAN G. BRINKMAN, of New York city, New York, have invented an Improved Electromotor, of which the following is a specification.

5 My invention relates to an improved construction of the armature, which I provide with a surrounding soft-iron jacket. This jacket not only serves as a means for attaching the armature to its shaft by a pair of heads or spiders, but it also serves to produce a uniformity in the magnetic flux that passes through the armature.

10 In the accompanying drawings, Figure 1 is an end view of my improved electromotor; Fig. 2, a vertical longitudinal section on line 2 2, Fig. 1; Fig. 3, a cross-section on line 3 3, Fig. 2; Fig. 4, a horizontal section, partly in plan, on line 4 4, Fig. 1. Fig. 5 is a cross-section of 15 one of the field-magnet plates on line 5 5, Fig. 3; and Fig. 6, a similar section of one of the armature-plates on line 6 6, Fig. 3.

20 The letters *a* represent a pair of frames that are connected by bolts *c*, which pass through the field-magnets. The frames *a* are provided with proper bearings, in which turns the armature-shaft *b*. Upon this shaft are mounted a pair of heads or spiders *d*, made of non-conducting material and provided with 25 flanged rims. These rims form the supports for a tubular soft-iron jacket *e*, Fig. 4, which is in this way secured concentrically to and revolves with the shaft *b*. The heads *d* have tapped eyes that engage correspondingly-threaded sections *b'* of shaft *b* and permit the heads to be screwed up until the jacket *e* is 30 properly seated.

25 Within the jacket *e* are contained the armature-plates *f*, connected by bolts *f'* and the armature-winding *g*, the latter passing with 40 its ends through perforations in one of the heads *d* to the commutator *h*.

35 The jacket *e* should be of such a diameter as to be in metallic contact with the teeth of the armature-plates *f*, and in this way the jacket serves to equalize the magnetic currents passing through such plates and to produce a uniform magnetic flux from pole to pole. The length of the jacket should be 45 such that it projects beyond the ends of the winding and offers a large chamber for the reception of the coil. Thus the jacket forms a

means for sustaining the armature plates and coils and connecting them to the shaft in such a manner that a maximum quantity of work 55 may be extracted from such armature.

5 i are the plates constituting the field-magnets, and *j* are the field-magnet windings, all assembled in the usual manner. The current may enter at *k*, go to the windings *j*, thence 60 to commutator *h*, armature-winding *g*, and out at *l*, as usual.

What I claim is—

1. The combination in an electromotor of the armature-shaft with a pair of heads or spiders supported thereon, a jacket supported by the heads or spiders and armature plates and coils inclosed by the jacket, the ends of the jacket being in contact with the outer edges or teeth of the spiders, substantially as 65 specified.

2. The combination in an electromotor, of an armature-shaft having threaded sections with a pair of heads or spiders having tapped eyes adapted to engage said sections, a soft-metal jacket supported by said heads or spiders and armature-plates inclosed by and in contact with said jacket, the ends of the jacket being in contact with the outer edges or teeth 70 of the spiders, substantially as specified. 75

3. In an electromotor the combination of field-magnet plates and armature-plates composed of soft-metal bodies, with a soft-metal jacket inclosing the armature-plates, heads or spiders for supporting the jacket and an armature-shaft for supporting the heads or spiders, the ends of the jacket being in contact with the outer edges of the teeth of the spiders, 80 substantially as specified. 85

4. In an electromotor, the two frames *a*, 90 bolts *c*, for connecting them and which pass through the field-magnets, the shaft *b* journaled in said frames; the tubular soft-iron jacket *e*, and the non-conducting closed heads applied to the ends of the jacket, combined 95 with the plates *f*, and winding *g*, placed in the closed chamber, the field-magnet plates *i*, the winding *j*, suitable connecting-wires, and armature, substantially as described.

SEBASTIAN G. BRINKMAN.
